FURNITURE SPRING SUSPENSION

Charles C. Meutsch, Buffalo, N. Y.

Application November 5, 1932, Serial No. 641,389

1 Claim. (Cl. 155—179)

This invention relates to a spring suspension for chairs, davenports, etc., and more particularly relates to a spring suspension in which resilience is obtained principally by the use of band iron springs rather than the usual hour-glass, helical, cushion springs with their concomitant and complicated network of tie cords.

The principal object of the invention is to provide an inexpensive and easily installed spring suspension which provides a spring action in all respects equivalent to such a cushion spring construction,—not only as to the desired localized flexure consequent upon localized pressures but also as to the prevention of excessive vertical movement and disagreeable side sway of the spring suspension as a whole. Numerous other objects of the invention and practical solutions thereof are disclosed in detail in the herein patent specification, wherein:

20 In the accompanying drawings:

Fig. 1 is a top plan of a chair provided with my improved spring suspension, some parts being in section and other parts being broken away.

Fig. 2 is a vertical, longitudinal section thereof, taken on line 2—2, Fig. 1.

Fig. 3 is a vertical, transverse section thereof, taken on line 3—3, Fig. 1.

Fig. 4 is a vertical, longitudinal section, taken on line 4—4, Fig. 1.

30 Fig. 5 is a vertical, longitudinal section similar to Fig. 2 but showing a modified form of the invention.

Fig. 6 is an enlarged, fragmentary, vertical, longitudinal section showing a modified method 35 of hinging the main springs to the main frame.

Fig. 7 is an enlarged perspective of one of the extension spring clips of Figs. 1—5 prior to its being assembled.

Fig. 8 is a vertical, longitudinal section through 40 a chair provided with another modified form of the invention.

Fig. 9 is a fragmentary, horizontal section thereof, taken on line 9—9, Fig. 8.

Fig. 10 is an enlarged, fragmentary, perspective 45 of the wooden edge piece of Figs. 8 and 9 showing its connection with one of the extension springs.

Similar characters of reference indicate like parts in the several figures of the drawings:

50 My invention may be embodied in various forms and in furniture spring suspensions of various constructions, and the present applications are therefore to be regarded merely as some of the organizations which come within the scope of my 55 invention and satisfactorily carry out the func-

tion of same in practice. As here shown, and referring for the present to only Figs. 1—4, the same is constructed as follows:

The invention is here shown as applied to an ordinary, stiff backed, four-legged arm chair. 5 The main frame of such a chair comprises:—the rear legs 20, 20 joined together by the horizontal, transverse, rear, frame beam 21 and extending integrally upward to form the back pillars 22, 22;—the front legs 23, 23 joined together by 10 the horizontal, transverse, front, frame beam 24 and extending integrally upward to form the front pillars 25, 25;—and the horizontal, longitudinal, side, frame beams 26, 26 which connect the front and rear sets of legs.

15 Resting at its opposite ends upon said side frame beams 26, 26 is a horizontal, transverse draw bar 27 which is held rearwardly against the front faces of the rear pillars 22, 22 by one or more sheet metal straps 28, the forward end 20 of each of which is curled around said draw bar 27 and the rear end of each of which is bent sharply down against the rear face of the rear beam 21 and is secured in place by a nail 30,—a plurality of perforated holes 31 being formed in 25 said strap 28 to compensate for different widths of pillars 22 and to allow said nail 30 to be driven through the soundest available portion of said rear beam 21.

Extending forwardly of said draw bar 27 are a 30 plurality of substantially horizontal, helical, tension springs 32 the rear ends of which are provided with suitable curled portions or eyes which receive said draw bar 27. The front ends of said tension springs 32 are provided at their front ends 35 with similar curled portions or eyes which receive a pivot bar 33. The front curled end of each of said tension springs 32 also passes through a hole 34 formed in the rear end of a companion, arcuate main spring 35,—the same being supported at its 40 rear end upon aforesaid pivot bar 33 and retained in place by the front curled end of its companion tension spring 32 which passes through said hole 34 of said main spring 35 and encircles said pivot bar 33.

45 Each main spring 35 is of arcuate form and is constructed of rolled steel of rectangular cross section and having a sufficiently high carbon content (preferably heat treated) as to be very resilient without permitting fiber stresses beyond 50 the elastic limit of the metal. The front ends of these main springs (see Fig. 2) are resiliently connected to the main frame of the chair in a manner similar to the rear connection thereof, i. e., the front end of each main spring 35 rests 55

upon a front pivot bar 38a and is held in place thereon by the rear curled end of a companion tension spring 32a whose front curled end receives a front draw bar 27a held in place by one or more straps 28a and nails 30a.

So as to keep the rear ends of the main springs 35 in proper lateral position relatively to each other, the same are all secured together (by rivets 36 or otherwise) to a tie strip 37, the extreme 10 projecting ends of which are smoothly curled downward so as to avoid any sharp edges and also to prevent any possibility of lacerating the usual fabric covered padding (see Fig. 8) which is placed on top of the metal spring suspension. 15 Secured by a rivet 40 to the forward portion of each main spring 35 is a forwardly projecting extension spring 41, the rear end of the same being either provided with a plurality of holes 42 for the reception of said rivet 40, or otherwise 20 arranged to permit of having said extension spring project any desired distance forwardly to suit the particular size of the main frame in which the spring suspension is being installed. The front ends of the several extension springs 41 are 25 connected together by a wire edge piece 43, each extension spring being individually secured thereto by a U shaped, sheet metal retainer 44 and rivet 45. This edge piece prevents excessive undulations along the front edge of the spring 30 suspension after the padding has been placed in position. To further prevent such excessive undulations, said wire edge piece 43 is bent sharply rearwardly at its opposite ends at 46 and then bent horizontally inward to form the supplemental edge piece 47. The latter is secured to the 35 several extension springs 41 by sheet metal clips 48 (see Figs. 7, 2, and 1).

Each of said clips has a lower, flat, central body portion 50, which bears against the lower face of its companion extension spring 41, and is also provided with a pair of ears 51 which extend upwardly on opposite sides of said companion extension spring 41 and are bent or curled around the top of the adjacent part of the supplemental 45 edge piece 47. To avoid any metallic noises resulting from metal-to-metal contacts, a plurality of rectangular pieces of felt or other sound deadening material 52 are interposed between the bottom of said supplemental edge piece 47 and the flat, adjacent top faces of the extension 50 springs 41. A similar and longer strip of felt 53 is also placed between the lower face of each supplemental spring 41 and the upper face of the body portion 50 of its companion clip 48. This 55 strip of felt 53 extends forwardly and is received between the front, lower face of its companion extension spring 41 and the lower lip of its companion retainer 44, and is held in place by aforesaid rivet 45, the shank of which passes through 60 a suitable hole formed in the front end of said felt strip 53. It is to be noted that this felt strip 53 also prevents any metallic, noisy contact between the bottom of its companion extension spring 41 (when the same is depressed) and its 65 companion front tension spring 32a and strap 28a which are located immediately below.

To put an initial tension on the extension springs 41 and, to some extent also, on the main springs 35, one or more chains or other tension members 54 are provided, each of which is connected at its upper end with the wire edge piece 43 and is secured at its lower end by a nail 55 to the upper face of the front frame beam 24. 70 By the use of these tension members 54 the edge piece 43 is prevented from raising up excessively 75

high when the chair is not in use. In other words, the use of the tension members 54 ensures that the front portion of the cushion will only commence to flex downwardly after a certain minimum amount of pressure is applied to its upper surface. This in no way detracts from the resiliency of the spring suspension, but only prevents it from raising up to extreme upward positions in which positions its resilient strength is so slight as to be negligible. These tension members 54 also prevent slackness from occurring at any time in the connections between the main springs 35 and the main frame, and hence prevent any noisy rattling of the parts when the pressures on the spring suspension are changed. 15

To prevent disagreeable and inefficient side sway of the whole spring suspension relatively to the main frame, a pair of limiting chains or similar lateral, flexible members 56 are provided. Each of these flexible, lateral members 56 is secured at its upper end by a rivet 57 to the central portion of one of the endmost main springs 35a and extends laterally and outwardly down to the upper face of the adjacent side frame beam 26 where it is secured by a nail 58. Preferably, 20 these lateral members 56 are sufficiently short as to be compelled to sustain a tensile strain when assembled in position. The reasons for such a tensile strain are similar to the reasons for providing an initial tensile strain in the tension members 54, i. e., to avoid unnecessary vertical movement of the spring suspension and to avoid noises resulting from slack metallic connections. 25

The individual, endmost main springs 35a are 30 aided in their resilient opposition to a superimposed load by companion main springs 35 located on only the one side of said endmost main springs 35a, whereas all of the central main springs 35 are 35 aided on both sides by adjacent companion main springs 35. It is therefore evident that the endmost main springs 35a should have a greater, independent, resilient strength than the rest of the main springs 35. This is accomplished in the present invention without necessitating specially 40 constructed, end, main springs for this purpose. As shown in Fig. 4, a stiffening, helical spring 60 is interposed between the ends of each of the endmost main springs 35a, the same being connected thereto by suitable chains or other flexible members 61. The amount of tension exerted by each 45 of said stiffening springs 60 may be adjusted so as to best fulfill the particular requirements desired, by passing either of the eyes of said stiffening spring through any desired one of the links in its companion flexible member 61. After such a tension adjustment has been made it is preferred that any superfluous links which may be 50 dangling at the end of said flexible member be severed from the useful portion of said flexible member, as otherwise such superfluous dangling links are apt to cause a certain amount of noise whenever the pressures on the spring suspension 55 are suddenly changed. 60

The present invention is also applicable to the 65 spring suspension of "love seats", davenports, couches, etc. Where the length of such pieces of furniture are not very great, the spring suspension may be constructed substantially like that just described. Where, however, the piece of furniture is of considerable length, as in a davenport, it is preferred to have a plurality of sets of main springs of the type shown in Fig. 1, each set having its individual tie strip 37, its individual edge piece 43, etc. 70

In Fig. 5 is shown a simpler and less expensive form of the invention. In this case the front tension springs 32a are dispensed with, the front ends of the main springs 351 being individually hinged 5 at 62 directly to the front frame beam 241. In this construction the rear leaf of each hinge 62 is secured by a rivet 63 to the front end of its companion main spring 351, while the front leaf of said hinge lies upon the horizontal, upper 10 face of the front frame beam 241 and is bent sharply downward against the front face of said beam and is secured in place by a nail 64. The strains upon this hinge 62 are chiefly vertical, by reason of the fact that, as the main springs 351 15 are flexed, the rear ends thereof are free to move rearwardly as well as downwardly.

Where a piece of furniture is used very roughly, the loads imposed on the spring suspension may contain horizontal as well as vertical components. To positively ensure that such horizontal components will not loosen the hinged connection between the main springs and the main frame, the construction of Fig. 6 may, if desired, be adopted. In this case the rear leaf of the hinge 25 622 is secured to the front end of its companion main spring 352 just as in Fig. 5. The front leaf of said hinge 622 is, however, somewhat different, extending upwardly from the hinge pivot so as to lie against the inner, vertical face of the 30 front frame beam 242, and being then bent sharply and horizontally forward so as to lie on the top face of said beam, and then bent sharply downward so as to lie against the front vertical face of said beam where it is secured by a nail 642. 35 Such a hinge construction is capable of sustaining heavy, horizontal, forward load thrusts as well as the ordinary vertical load pressures.

Figs. 8-10 illustrate a very inexpensive and very satisfactory commercial form of the invention. In this construction the main springs 353, 40 rear tension springs 323, extension springs 413, etc. are arranged substantially as in Fig. 5. The edge piece 433 is, however, of different form, being constructed of a strip of wood "moulding" of 45 special cross section with its front edge thick and rounded and its rear edge tapered. Said wooden edge piece 433 is secured in place by a number of countersunk wood screws 65 subsequently to the time when the rest of the spring suspension has been secured in place, thereby 50 allowing said edge piece to be moved to the desired longitudinal position (determined by the particular proportions of the main frame being equipped) and then screwed to the extension springs 413 in this particular position.

In applying the padding, etc. to this form of the invention, the base fabric 66 is first laid over the wooden edge piece 433 which latter is at this time

lying on a suitable bench jig or fixture. The front fabric 67 and cover 68 are then blind tacked with the tacks 70 to the rear, upper, bevelled face of said wooden, edge piece 433. The front portion of the base fabric 66 is then tacked by tacks 71 5 to the vertical front rabbeted face of said edge piece 433. Said wooden edge piece is now laid with its several fabrics on the extension springs 413 and is secured in proper position by means of the wood screws 65, after which the rear part of 10 the base fabric 66 is tacked to the rear frame beam 213 by tacks 72. The main padding 73 and front padding 74 are now laid evenly over the base fabric 66 and the rear part of the cover 68 tacked to the rear frame beam 213 by tacks 75. 15 The front part of the front fabric 67 is now blind tacked at 76 to the front face of the edge piece 433 together with the face fabric 77. The whole spring suspension is now pressed down and the depending front portion of the base fabric 66 20 tacked to the front frame beam 243 with tacks 78, thereby putting a tensile strain in this portion of the base fabric 66 and constituting thereof a tension member 543 which functions similarly to the tension member 54 of Figs. 2 and 4. 25 The lower portion of the depending face fabric 77 is now tacked to the bottom of the front frame beam 243 by tacks 80. It is to be understood, of course, that the foregoing padding arrangement is one of relatively simple form, and that, in usual 30 practice, a considerably more elaborate arrangement of padding and fabric is employed.

Attention is directed to Fig. 9 which shows that by this use of a wooden edge piece 433, the two fabrics lying upon said edge piece 433 (namely 35 base fabric 66 and front fabric 67) may be folded around the ends of said edge piece and tacked in place by tacks 81 so as to enable said fabrics to be disposed in close juxtaposition to the inside faces of the two front pillars 253. This makes a 40 neat and attractive construction at this point. After said tacks 81 have been driven into place, the face fabric 77 is bent (not folded) around the end face of said edge piece 433 and is tacked thereto, so that when said face fabric 77 is thus 45 in final position, it lies in place flat and unwrinkled (except, of course, for the horizontal wrinkles which occur temporarily when the whole spring suspension is depressed).

I claim as my invention:

A furniture spring suspension comprising a frame; a plurality of main springs each of which is connected at one end with said frame; a pivot bar connecting the other ends of said main springs; a draw bar connected to said frame and 55 a resilient connection between said pivot bar and said draw bar.

CHARLES C. MEUTSCH.
